(57) **CLAIM**

The ornamental design for a pair of shoes, as shown and described.

DESCRIPTION

FIG. 1 is a top plan view of a pair of shoes, showing my new design; and,

FIG. 2 is a right side elevational view thereof.

The shoe shown is the right shoe of a pair of shoes; the left shoe (not shown) is a mirror image of the shoe illustrated. The sole of the shoe is not part of the claimed design and is therefore not illustrated.
